UNITED STATES PATENT OFFICE.

NELS H. HASSEL, OF BEVERLY HILLS, CALIFORNIA.

MULTIPLE MUFFLER AND CONTROL THEREFOR.

1,332,663.

Specification of Letters Patent.

Patented Mar. 2, 1920.

Application filed June 10, 1919. Serial No. 303,494.

To all whom it may concern:

Be it known that I, NELS H. HASSEL, a citizen of the United States, residing at Beverly Hills, in the county of Los Angeles, State of California, have invented a new and useful Improvement Comprising Multiple Mufflers and Controls Therefor, of which the following is a specification.

My invention relates to internal combustion engines and more particularly to engines having eight or more cylinders. In all internal combustion engines used in automobiles it is common practice to provide a muffler in the exhaust pipe for the purpose of muffling or deadening the noise of the explosion. Where a single muffler is so used considerable back pressure develops, which detracts from the power of the engine so that it is common practice to provide a muffler cut-out which is opened when it is necessary to call upon the engine for extra power. These muffler cut-outs are objectionable in that the engine makes a lot of noise when they are open, and the use of cut-outs is restricted by law in certain localities.

An object of my invention is to provide an arrangement whereby the exhaust of the engine can be muffled without producing any appreciable back pressure. This I accomplish by providing a separate muffler for each cylinder. It might be explained that where a single muffler is used on an eight or twelve cylinder engine the explosions follow each other so closely that there is a continuous pressure on the muffler and a continuous loss of power. By providing a muffler for each cylinder the hot gases from each cylinder have sufficient time to expand before more hot gases from another cylinder are introduced so that comparatively little back pressure is produced.

Further objects and advantages will be made evident hereinafter.

Referring to the drawings, which are for illustrative purposes only,

Figure 1 is a side elevation partly in section showing an embodiment of my invention.

Fig. 2 is a section on a plane represented by the line 2—2 of Fig. 1.

Fig. 3 is a section on a plane represented by the line 3—3 of Fig. 1.

Fig. 4 is a section through the connection between the valve crank and its operating bar.

In the embodiment of my invention shown in these drawings a portion of an eight-cylinder engine is shown, this engine having exhaust opening 11, to which is secured by means of bolts 12 exhaust conduits 13. These exhaust conduits extend downwardly and are provided with a plurality of small holes 14 around the periphery thereof, the bottom of the conduit 13 being open. Secured about the lower portion of the conduit 13 is a cylindrical diaphragm 15, also having a plurality of small holes 16 therein. Surrounding the diaphragm 15 is a shell 17, which is tightly secured at 18 to the conduit 13, and which is provided with a tight bottom 19, which is secured by means of a flange 20 to a short pipe 21, which is secured in an exhaust pipe 22. Closing the opening in the bottom of the conduit 13 is a valve 23, which is pivoted on a shaft 24, provided with a crank 25. All of the cranks 25 are secured to an operating bar 26 by means of a thumb screw 27 which passes through a loose cushion 28. The operating bar 26 may be operated from the dash of the car by any convenient means not shown, to open and close the valve 23.

The method of operation is as follows:

The valve being normally closed as shown in Fig. 1, the engine is started, each cylinder exhausting through its conduit 13. The hot gases from the conduits 13 when the valves 23 are closed, pass successively through the openings 14 and 16, the rate of expansion through the different openings differing slightly, so that in the place of a short sharp noise, due to the sudden expansion, this noise is spread over a considerable time, with the result that it is not noticeable. By providing a plurality of mufflers a cushion is provided on each cylinder and the amount of back pressure is very greatly reduced. In addition it is possible, by disconnecting the thumb nuts 27 to allow one cylinder to discharge directly by opening its valve 23 so that the noise of this cylinder can be listened to apart from the others, which is of great assistance in determining the performance of the engine, and locating trouble in any

cylinder. When it is desired to entirely put the mufflers out of action all of the valves 23 are opened and the hot gases discharge directly from the conduit 13 into the short pipes 21, which are of the same size as the conduits 13 and directly in line therewith.

An incidental advantage of my invention is that the muffler stands vertical and any 10 of the carbon, which tends to accumulate therein, when shaken off, falls directly into the exhaust pipe and is blown out with the exhaust gases.

A further advantage of my invention is 15 that even with the valves 23 open that the engine exhausts into a regular exhaust pipe 22, so that the gases are carried back to the rear of the machine and not released under the floor or under the hood of the 20 engine.

I claim as my invention:

1. In combination with an internal combustion engine having a plurality of cylinders; a common exhaust pipe; a plurality 25 of mufflers, each muffler being connected between one of said cylinders and said exhaust pipe; walls forming an unrestricted passage through each muffler; and a plurality of valves, each valve closing one of said 30 sages.

2. In combination with an internal combustion engine having a plurality of cylinders; a common exhaust pipe; a plurality 35 of mufflers, each muffler being connected between one of said cylinders and said exhaust pipe; walls forming an unrestricted passage through each muffler; a plurality of valves, each valve closing one of said pas-

sages; and means by which all of said valves can be simultaneously operated. 40

3. In an internal combustion engine having a plurality of cylinders, each cylinder having an exhaust opening on the side and externally near the top thereof; a common exhaust pipe parallel to the shaft of the 45 engine and to one side and near the bottom thereof; and a series of vertical mufflers each connected between one of said exhaust openings and said exhaust pipe.

4. In an internal combustion engine having a plurality of cylinders, each cylinder having an exhaust opening on the side and externally near the top thereof; a common exhaust pipe parallel to the shaft of the engine and to one side and near the bottom 55 thereof; a series of central conduits each connected to one of said exhaust openings and extending vertically downward above said exhaust pipe, said conduits each being perforated to allow gas to escape there- 60 through; a series of shells each tightly secured around said conduit and having a single opening connected to said exhaust pipe; a series of valves each normally closing the bottom of said conduit and thus shutting off direct connection between said conduit and the interior of said shell; a series of cranks each arranged to operate one of said valves; and a common connection through which all of said cranks may be 65 operated.

In testimony whereof, I have hereunto set my hand at Los Angeles, California, this 4th day of June, 1919.

NELS H. HASSEL.
